UNITED STATES PATENT OFFICE.

FREDERICK G. GRUEN, OF CINCINNATI, OHIO, ASSIGNOR TO THE GRUEN WATCH COMPANY, OF CINCINNATI, OHIO, A CORPORATION OF OHIO.

DESIGN FOR A WRIST-WATCH DIAL.

Application filed December 9, 1925. Serial No. 15,702. Term of patent 7 years.

To all whom it may concern:

Be it known that I, FREDERICK G. GRUEN, a citizen of the United States of America, and a resident of Cincinnati, in the county of Hamilton and State of Ohio, have invented a new, original, and ornamental Design for a Wrist-Watch Dial, of which the following is a specification, reference being

had to the accompanying drawing, forming part thereof.

The figure is a plan view of a wrist watch dial, showing my new design.

I claim:

The ornamental design for a wrist watch dial, as shown.

FREDERICK G. GRUEN.
